(57) **CLAIM**

The ornamental design for a lighting assembly, as shown and described.

DESCRIPTION

FIG. 1 is a perspective view of a lighting assembly showing my new design;

FIG. 2 is a first side elevational view thereof;

FIG. 3 is a second side elevational view thereof, opposite from the first side of FIG. 2;

FIG. 4 is a first end elevational view thereof;

FIG. 5 is a second end elevational view thereof, opposite from the first end of FIG. 4; and,

FIG. 6 is a top plan view thereof.

The bottom of the design is flat and unornamented.
